FREQUENCY MODULATION RADIO
TRANSMITTER

John C. Geist, Avon, N. J.

Application November 13, 1945, Serial No. 628,342

6 Claims. (Cl. 332—17)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention relates to radio transmitter systems. More particularly, the present invention relates to frequency modulation transmitter systems, and has for its primary object to provide a simplified and low cost system of the character referred to for general radio signal communication.

It has been customary to use amplitude modulation for radio telephone transmission in the minor or low power classes of stations as distinguished from commercial and high fidelity stations using higher power and costlier equipment and in more complicated circuit networks. Furthermore, frequency modulation networks heretofore used for broadcast signals have had the disadvantage of requiring specially designed components and complex circuits requiring adjustment to a high degree of tolerance and are relatively expensive.

It is also an object of this invention to provide a new and improved frequency modulation system for radio signal transmission that is less complicated, and limited in its requirements for circuit components and operational adjustments.

It is a further object of the invention to provide a new and improved frequency modulation system or network for general radio signal transmission that is simple in structural requirements, is of ample practical capacity and avoids the customary critical requirements in values and types of equipment considered essential in conventional networks.

A still further object of the present invention is to provide a new and improved frequency modulation network for minor radio telephone transmission that will retain all the general inherent advantages of frequency modulation signal transmission without involving its customary complexity and cost.

For a better understanding of the invention and further objects thereof, reference is made to the accompanying drawings and the following description while the scope of the invention is particularly pointed out in the appended claims.

Referring to the drawings:

Figure 1 is a schematic circuit diagram of a frequency modulation transmitter system embodying the invention, and

Figure 2 is a view in perspective of a signal transmitter device constructed in accordance with

with the invention to include the system of Figure 1.

Referring to Figure 1, the transmitter system may be considered to comprise six main sections, as follows: A modulator 3, an oscillator 4, a primary multiplier amplifier 5, an auxiliary multiplier amplifier 6, a final stage amplifier 7, and a radiator device or antenna 8.

The oscillator is preferably of a type shown, comprising an oscillator tube 10 having a tuned tank circuit 11 connected between the anode 12 and the control grid 13. The tank circuit is connected directly with the anode and is coupled to the control grid through a suitable anode current blocking capacitor 14. The grid circuit is completed to ground and cathode through an R. F. choke coil 15 and a grid bias resistor 16. The tank circuit for the oscillator comprises a tuning inductance 17 shunted by a split-stator tuning capacitor 18—19.

The tuning inductance 17 is provided with tap 20 through which anode current is applied to the tube 10 from an anode current supply circuit 21—22 connected with a positive supply terminal 23. Interposed between the supply lead 21 and the tap 20 is an R. F. choke coil 24 and an audio-frequency or modulation choke coil 25 in series, the R. F. choke coil being connected more adjacent to the tap 20 on the oscillator tuning inductance.

In a transmitter designed to operate in the frequency range between 112 and 115.5 megacycles, a commercial type 7C5 tube at 10 has been found to be satisfactory, with the screen grid 26 connected to the anode, and has been operated as a self-excited ultra-audion oscillator on a frequency of 56.5 megacycles. The anode voltage applied to the tube was of the order of 180 volts with an anode current of approximately 28 milli-amperes. The voltage provided at the positive terminal 23 may be lowered to the proper voltage for the anode through a suitable series resistor indicated at 27 in the anode current supply circuit lead 21.

The oscillator is amplitude modulated at a relatively low percentage modulation by a suitable amplitude modulation means referred to generally in the unit 3 and comprising in the present example, a microphone 30 representing any suitable source of modulation signals coupled through a microphone transformer 31 and a modulation gain control potentiometer 32 with a self-biased amplifier tube 33. The output or anode circuit 34 of the tube 33 is coupled through an output lead 35 and a coupling capacitor 36 with a point

37 on the anode circuit of the oscillator located between the R. F. choke 24 and the audio-frequency choke 28, thus introducing into the oscillator anode circuit the modulating frequency from the amplifier 33 resulting from speech or other audio-frequency sound being applied to the microphone 30 in the usual manner.

The audio-frequency output of the amplifier tube 33 is derived from an audio-frequency choke coil 38 connected in the anode circuit 34 between the anode 39 and the positive anode current supply terminal 23. A common return supply terminal 40 is connected to ground and to the cathodes of the oscillator and the amplifier as shown. A suitable battery 41 connected between terminals 23 and 40 is indicated as a source of anode current, although any other suitable direct current source of supply may be used.

Any suitable means may be provided for amplitude modulating the oscillator. In the present example, the output from the modulator is applied to the oscillator through the terminal 31 between the oscillator tuning inductance 17 and the modulation choke coil 25, whereby the effective anode voltage of the oscillator is varied in accordance with the modulation frequency. Amplitude modulation of the self-excited oscillator causes frequency modulation of the oscillator, that is, variation of the frequency existing in the tank circuit 11.

To provide frequency multiplying and to remove from the output of the oscillator the amplitude modulation component of the resulting signal, the oscillator is coupled to the multiplying amplifier 5 which is of the class C type and comprises an amplifier tube 45, which is biased beyond cutoff, a tuned input circuit 46, and a tuned output circuit 47. A suitable source of bias potential is indicated at 114. The tuned input circuit includes a tuning inductance 48 provided with a shunt tuning capacitor 49, the inductance being coupled to the tuning inductance of the oscillator, as shown, for transferring energy therefrom. The frequency of this circuit is the same as that of the oscillator, while the output circuit 47 is provided with a tuning inductance 50 and a shunt tuning capacitor 51 to provide tuning to a multiple of the oscillator frequency such as, in the present example, 113 megacycles. The amplifier tube 45 may be of the commercial type 7C5, operating, as described, as a class C doubler inductively coupled to the oscillator. The tuning inductance 48 is tapped as indicated at 52 to provide a connection to ground for the input grid through a grid resistor 53, the cathode circuit 54 being likewise connected to ground. The resistor 53 is bypassed by a capacitor 55. A coupling capacitor 56 is also connected between the low potential side of the circuit 46 and the cathode circuit and ground.

Anode current is supplied to the tube 45 through the tuning inductance 50, an R. F. choke coil 60, and an anode voltage dropping resistor 61 from the supply lead 22. The tank circuit 47 is by-passed at its low potential side to cathode and ground through a suitable by-pass capacitor 62. The screen grid circuit indicated at 64 is connected with the output end of the potential dropping resistor 61 through an isolating resistor 65, provided with a by-pass capacitor 66 for effecting filtering of the potential on the screen grid.

With the foregoing arrangement the output frequency of the oscillator is effectively doubled.

and since the depth of modulation is kept low, the amplitude modulation component of the oscillator signal is substantially eliminated by the succeeding class C amplifier stage 5. However, the frequency modulation component of the signal remains and the frequency deviation is multiplied also by the stage 5, resulting in an output from a transmitter in which this system is used of a virtually constant amplitude frequency-modulated carrier wave.

The frequency doubling and amplitude-modulation-eliminating amplifier stage 5 is representative of any desired number of such stages which may follow the oscillator circuit in cascade connection, such as the succeeding amplifier stage 6 which is also of the class C type. This comprises an amplifier tube 70 having an input grid 71 coupled across an input grid resistor 72 and through a coupling capacitor 73 with the high potential or output side of the tuned anode circuit 47 of the preceding amplifier stage 5.

The amplifier 70 is provided with a suitable tuned output circuit 74, comprising a tuned inductance 75 shunted by a variable tuning capacitor 76 in the anode circuit thereof. Anode current is supplied from the supply lead 22 and the terminal 23 through a supply circuit indicated at 77 and a suitable R. F. choke coil 78 interposed between the lead 77 and the low potential side of the tuning inductance 75. The anode circuit is by-passed to ground and cathode through a by-pass capacitor 79. The screen grid circuit 80 is likewise by-passed to cathode through a suitable by-pass capacitor 81 and is supplied with operating current through a potential dropping and filtering resistor 82 from the supply lead 11. The bias for the grid 71 is obtained from a source 115.

The final amplifier stage may be of any suitable type and in the present example comprises the usual output amplifier tubes indicated at 85 and 86, connected in push-pull relation between a tuned input circuit 87 and a tuned output circuit 88. Anode and other operating potential may be obtained from any suitable source indicated by supply terminals 89 and 90. In the present example, a battery 91 is connected with terminals 89 and 90 as a source of anode circuit. In a practical embodiment of the invention which was found to be effective, the elements of tubes 85 and 86 were embodied in a commercial type tube 832 with an operating potential of 450 volts supplied at the terminals 89 and 90.

The output circuit 88 is coupled through a coupling coil or other suitable means indicated at 95 with ground 96 and the radiator or antenna referred to at 8, while the input circuit is coupled to the last stage of the multiplying amplifier through any suitable means, such as a link circuit or transmission line 97 having an input coupling coil 98 coupled with the tuning inductance 75 and an output coupling winding 99 coupled with the tuning inductance 100 of the input circuit 87 for the final stage amplifier. The grid circuits in this case, are biased from source 116.

From the foregoing description, it will be seen a radio transmitter system in accordance with the invention comprises a self-excited oscillator; means for amplitude modulating the self-excited oscillator with a low percentage modulation by varying the anode or plate voltage thereof, such means including a modulation input connection between a modulation choke coil in the anode circuit of the oscillator and a tap on the tuned oscillator circuit. The system further comprises

one or more multiplier stages of the class C type, whereby the amplitude modulation component of the generated signal is removed. In the present example with the audio-frequency output of the modulator superimposed upon the oscillator anode voltage, the percentage modulation is limited to a low value by controlling the output voltage of the modulator, such as by adjustment of the gain control device 32.

Since the oscillator is thus amplitude modulated at a low percentage modulation and being of a self-excited type, the variation in anode voltage in the oscillator tube 10 produces a variation in frequency in the oscillator circuit. That is, frequency modulation of the oscillator is developed by the audio frequency output of the modulator. The output of the oscillator is supplied to the amplifier stage 5 which functions to increase the amplitude of the voltage from the oscillator, to multiply the frequency of the oscillator output signal, and to suppress the amplitude modulation component. This is because the depth of modulation is maintained at a low value, and at the same time the frequency deviation of the frequency modulation component is multiplied by the succeeding amplifier stages. The resulting output from the final stage amplifier and the radiator 8 is a substantially constant amplitude frequency modulated carrier wave.

In designing any specific equipment using the present method of modulation, the depth of the amplitude modulation, the oscillator frequency, and the oscillator L/C ratio are selected so that sufficient grid drive power is available between modulation peaks whereby the multiplier stages will increase the frequency deviation to a required amount at the desired output frequency. For this purpose, any number of additional stages represented by the stage 6 may be added to the stage 5.

During tests to determine the operating efficiency of the system described, it was found that frequency modulation was accomplished with practically no resultant amplitude modulation and that the transmission with frequency modulation resulted in communication equally as good in every respect as that resulting from amplitude modulation of the final stage amplifier. Furthermore, frequency modulation signals from a system substantially as described and embodying the invention, is received best with a broad intermediate frequency channel indicating that the frequency deviation was wider than normal amplitude modulation sidebands.

Furthermore, with the system described, no critical adjustment is required for any of the components other than adjustment of the modulator output for low percentage modulation. Because of the simplicity of the circuit employed and the relatively few number of component parts involved, a battery power transmitter may be provided in a relatively small space adapted for portable use. For example, the circuit of Figure 1 may be embodied in a portable transmitter having a form substantially as shown in Figure 2, to which attention is now directed along with Figure 1.

The component elements 3, 4, 5, 6, and 7 may be located in sectional units 102, 103, 104, 105, and 106, respectively, of Figure 2. Each of the 7 units consists of a suitable shielded casing which may be joined and connected to form a single transmitter unit with the antenna or radiator 107 extending vertically and supported by insulated rear bracket means 108 and 109. The 7

microphone or other speech input device is located at the top of the unit as indicated at 110. The battery power may be provided by suitable elements carried within handle members indicated at 111 and 112 on each side of the unit, and connected therewith by bracket means 113, as indicated. By providing the battery power in the handles of the device the individual battery units may be made accessible for inspection and repair, and effects a reduction in the overall size of the main housing of the unit. Furthermore, by providing the device in sections, any one may be removed for replacement and repaired more readily than if they were provided in a unitary case, as a single instrument.

Thus far the invention has been shown and described in one of its present preferred forms both as to circuit and as to structure. Other embodiments thereof may be made without departing from the principles, spirit and scope of the invention as defined in the claims.

I claim:

1. A radio transmitter system comprising in combination, a self-excited oscillator including an oscillator tube having a cathode, an anode and a control grid, a tuning inductance connected between the anode and control grid thereof, a tap on said inductance, circuit means for applying controlled anode current to said tube through said tap, means connected with said tap for superimposing amplitude modulation signals on said anode current, an amplifier biased beyond cutoff coupled with said tuning inductance for receiving the modulated signal output from said oscillator and for deleting the amplitude modulation component of said signal, and means for controlling the degree of amplitude modulation applied to said oscillator, whereby effective frequency modulation within predetermined operational limits may be provided.

2. The combination with a self-excited oscillator comprising an oscillator tube and a tunable oscillator tank circuit therefor of means for supplying anode current to said oscillator through said tank circuit, means for applying amplitude modulation signals to said anode current whereby the oscillator is frequency-modulated, means for limiting the depth of amplitude modulation applied to said oscillator to a low degree, and an amplifier biased beyond cutoff coupled to said oscillator to receive the modulated signal output therefrom and to delete the amplitude modulation component of said signal whereby effective frequency modulation within predetermined operational limits may be provided.

3. The combination with a self-excited oscillator comprising an oscillator tube and a tunable oscillator tank circuit therefor of means for supplying anode current to said oscillator through said tank circuit, means for applying amplitude modulation signals to said anode current whereby the oscillator is frequency-modulated, means for limiting the depth of amplitude modulation applied to said oscillator to a low degree, and an amplifier biased beyond cutoff coupled to said oscillator to receive the modulated signal output therefrom and to delete the amplitude modulation component of said signal, and means connected with said last-named amplifier for multiplying the output frequency of the signal delivered by said oscillator, whereby the frequency deviation range of the resultant frequency modulated signal is increased and available for transmission, the degree of said amplitude modulation being low enough to provide sufficient voltage to

drive the grid of said amplifier between modulation peaks.

4. A frequency modulation system comprising audio-frequency modulator means, a self-excited oscillator having an anode circuit coupled to said modulator means for receiving the modulation signal output thereof, means for controlling said modulation signal output to cause low percentage amplitude modulation of said oscillator, means for effecting variation in oscillator frequency in response to variations in the modulation signal, and an amplifier biased beyond cutoff coupled to said oscillator to suppress the amplitude modulation component of the oscillator signal output and provide a final signal for transmission at predetermined frequency, said percentage being low enough to provide sufficient voltage to drive the grid of said amplifier between modulation peaks.

5. A frequency modulation system comprising audio frequency modulator means, a self-excited oscillator having an anode circuit coupled to said modulator means for receiving the modulation signal output thereof, means for limiting and controlling said modulation signal output to cause low percentage amplitude modulation of said oscillator, means for tuning and controlling said oscillator to cause effective variation in the frequency thereof in response to the modulation signal output to provide effective frequency modulation signals, and a frequency multiplying amplifier biased beyond cutoff coupled to said oscillator to increase the effective frequency deviation range and to suppress the amplitude modulation component of the signal output and provide a resultant signal of predetermined frequency for radiation, said percentage being low enough to provide sufficient voltage to drive said amplifier above cutoff between modulation peaks.

6. A frequency modulation system comprising audio frequency modulator means, a self-excited oscillator having an anode circuit coupled to said modulator means for receiving the modulation signal output thereof, means for limiting and controlling said modulation signal output to cause low percentage amplitude modulation of said oscillator, means for tuning and controlling said oscillator to cause effective variation in the frequency modulation signals, a frequency multiplying amplifier biased beyond cutoff coupled to said oscillator to increase the effective frequency deviation range and to suppress the amplitude modulation component of the signal output, an auxiliary amplifier biased beyond cutoff coupled to said first named amplifier for further multiplying the output signal frequency thereof to a predetermined value, and means for further amplifying and radiating the resultant frequency modulated output signal from said auxiliary amplifier, said percentage being low enough that each cycle of voltage derived from the oscillator is high enough to render said amplifiers conducting between modulation peaks.

7. A frequency modulation system comprising audio frequency modulator means, a self-excited oscillator having an anode circuit coupled to said modulator means for receiving the modulation signal output thereof, means for limiting and controlling said modulation signal output to cause low percentage amplitude modulation of said oscillator, means for tuning and controlling said oscillator to cause effective variation in the frequency modulation signals, a frequency multiplying amplifier biased beyond cutoff coupled to said oscillator to increase the effective frequency deviation range and to suppress the amplitude modulation component of the signal output, an auxiliary amplifier biased beyond cutoff coupled to said first named amplifier for further multiplying the output signal frequency thereof to a predetermined value, and means for further amplifying and radiating the resultant frequency modulated output signal from said auxiliary amplifier, said percentage being low enough that each cycle of voltage derived from the oscillator is high enough to render said amplifiers conducting between modulation peaks.
